UNITED STATES PATENT OFFICE.

DWIGHT S. RICHARDSON, OF NEW YORK, N. Y., ASSIGNOR TO RICHARDSON & BOYNTON CO., OF NEW YORK, N. Y., A CORPORATION OF NEW YORK.

FURNACE.

Application filed January 9, 1925. Serial No. 1366.

This invention relates to improvements in furnaces.

One of the objects of the invention is to provide an improved furnace construction by 5 the use of which a more efficient burning of the fuel will take place.

It is another object to furnish a device of the character stated which when used will insure combustion in such a manner that 10 clinkers, dead spots, etc. in the body of the fuel will be minimized.

An additional object is to construct a furnace which will function in such a manner that the need of frequent cleaning of its 15 various internal surfaces and the flue connected with the outlet pipe thereof will be reduced.

Another object is to design a furnace construction by which the same amount of fuel 20 as heretofore will produce a more usefully available heat, and in which the response to the opening of the drafts and other control devices will be more rapid than has heretofore been the case.

25 Specifically, it is another object to furnish a mechanism by means of which the combustible gases liberated under normal conditions by the bed of fuel will be ignited and consumed, this being accomplished by a construction which will furnish air to the combustion chamber of the furnace, the device being of such a type that it may be readily renewed by a layman in the event of its burning out or being otherwise rendered unfit for 30 further service.

Still another object is that of constructing a mechanism of the type defined in the previous paragraph, the use of which will not necessitate any radical reconstruction of boilers or furnaces as now in use, and which 40 mechanism may be readily manufactured and applied to a furnace with ease.

Other objects of the invention will in part be obvious and will in part appear herein- 45 after.

The invention accordingly comprises the features of construction, combination of elements, and arrangement of parts which will be exemplified in the construction herein- 50 after set forth, and the scope of the application of which will be indicated in the claims.

For a fuller understanding of the nature and objects of the invention reference should be had to the following detailed description

taken in connection with the accompanying 55 drawings, in which:

Fig. 1 is a sectional side view of a furnace with a construction embodying one form of the present invention associated therewith;

Fig. 2 is a sectional front view thereof; 60

Fig. 3 is a top plan view of the device afore referred to; and

Fig. 4 is a bottom plan view thereof.

In the present exemplification the invention has been illustrated in connection with a 65 furnace of the steam or hot water type. While the subject matter of the present case is particularly intended for use in connection with heaters of household size, it will be understood that the invention may be utilized to advantage in connection with numerous 70 different types of water and steam boilers, air heaters, etc.

Thus, in these views the heater includes 75 a fire-pot, below which a grate is positioned, access to the fire-pot being had by means of a coal door 7, so that the combustion chamber of the furnace may be filled with fuel in the usual manner to approximately the level 80 indicated at 5'.

The fire-pot may be formed by utilizing a cylindrical or other shaped casing 5, which is jacketed by a second casing 8, encircling and disposed in spaced relationship to the first-named casing, so as to provide in the 85 present instance a heating jacket for water, which is introduced, as in the usual manner, through pipes communicating with openings in the exterior casing. The entire furnace assembly may also be supported upon a base 90 6, providing an ashpit, and, in the usual manner, the draft through the grate, as well as the removal of ashes from the pit, may be accomplished by means of a door 7', provided for this purpose. 95

Thus, the fuel burning within the fire-pot will serve to heat the water jacketed between the casings 5 and 8, and the products of combustion will move upwardly through the combustion chamber and past the sections 9, 10 100 and 11, by means of ports 12 provided in the latter for this purpose. In passing through these sections, which may be of any desired type, the temperature of the water will be raised, or in the event that the furnace is 105 of that type which is adapted to supply steam to a heating system,—and, consequently, the water level is below one or more of these sec-

tions—the steam emanating from the water level has its temperature materially raised within the sections, and after giving off heat to the uppermost section the products of combustion will pass through the flue pipe 13, the escape of gases from which may be controlled by dampers, etc.

It is here to be understood that a considerable amount of the products of combustion which pass through the ports 12 and into the outlet flue 13 are themselves combustible, but the heating units, incident to this capability, have heretofore been largely lost, due to the fact that there has been insufficient oxygen to permit complete combustion; or, where attempts have been made to ignite these gases, for example, by opening a port within the fuel door, they have proved to the greatest extent to be ineffective because the temperature of the air admitted was such that the desired result was not achieved. With this in mind efforts have also been previously directed towards introducing air within the combustion chamber and in preheating this air to such an extent that desirable combustion would be promoted. To a great extent, and particularly with respect to heaters of the household type, efforts along this line have also been unsatisfactory, for the reasons that the apparatus necessary to this result has required frequent renewal incident to the high temperature within the combustion chamber, and also due to breakage, so that considerable expense has been involved; but aside from this objection the greatest difficulty was because renewals of this nature have required the efforts of an experienced workman, and also it has been usually necessary to extinguish the fire in order to accomplish such renewal.

By means of the present invention the desired result, i. e., the burning of the combustible particles within the gases escaping from the body of fuel, are accomplished without the objections afore-enumerated coming into being. In the specific embodiment illustrated the rear end of the section 9 is reduced to a sufficient extent to provide an opening between the adjacent upper edges of the casings 5 and 8 and the section 10, which will be adequate for the passage of sufficient oxygen to promote combustion. Disposed within this opening in the present instance is the neck of an airbox 15, which neck is preferably offset as at 18, so that the body of the box may lie in a plane below that in which the mouth 19 of the neck extends. This box in cross-section, is preferably tapered, as has been best shown in Fig. 2, and has its lower surface provided with a plurality of longitudinally-extending slits 16, which will lie substantially centrally over the fuel body within the firepot, and well spaced from the upper surface thereof.

With a view to supporting this box in such a manner that it may readily be removed when

it is necessary, it will be observed that the upper surface 17 of the same is formed complementary to the under surface of the section 9, and the latter is provided with a supporting ledge 24 extending forwardly within the furnace. The outer edge of the airbox which projects beyond the ledge 24 is extended upwardly as at 20, and rearwardly as at 23, so as to form a hook for the purpose of bearing against the upper face of the ledge of section 9, it being noted that for the purpose of accommodating the parts this section is preferably formed with a recess 21 in its lower face, the length of this recess being more than equal to the depth of the ledge, plus the length of the rearwardly-extending portion 23. Thus, the airbox has two points of suspension, one adjacent the mouth 19 of its neck, and the other adjacent that edge which is nearest to the fuel door, and its discharge openings 16 are of such a nature that air will be efficaciously distributed within the combustion chamber in a manner hereinafter more particularly brought out.

In order to supply air to the box 15, a conduit 25 may be employed, which is suitably secured to the outer face of the casing 8, and has, in the present instance, its upper end in communication with the mouth 19 of the airbox neck, its lower end being in communication, through opening 26, with the outer atmosphere, and through an opening 28 with the ashpit.

In utilizing this device, and presuming that the furnace is just being started, a valve 27 may be turned in order to close direct communication between the pipe 25 and the outer atmosphere, but to allow communication between this pipe and the ashpit. A certain portion of the air sucked in through the door 7 will pass through the opening 28 and conduit 25. In passage through the latter it will be preheated to a certain extent, and upon being discharged into the neck of the airbox the temperature of this air will be further raised, due to the fact that this neck portion is preferably arranged to extend transversely of the port 12 of the lowermost boiler section, and is consequently in the path of the flames and products of combustion emanating from the upper surface of the fuel body 5'. Two factors will govern the discharge of air from within the box 15,—the first of these being pressure of the head of air within the conduit 25, and the second the amount of suction acting upon the mouths of the opening 16. In any event, it will be appreciated that as the fuel body is ignited and continues to burn, incident to the air which passes upwardly through the grate, flames will appear in the combustion chamber above the fuel body, incident to the partial combustion of the gaseous products discharged from this upper surface. Now, due to the fact that the upwardly-rising products of combustion,—as has been

indicated by arrows in Figs. 1 and 2—will be met by columns of heated air, virtually all of the burnable particles which exist in a state of suspension within the combustion products 5 will be consumed, incident to the fact that they will be immediately ignited upon the products of combustion being mixed with the highly heated air.

This will result in the entire interior of the 10 combustion chamber being, under normal conditions, virtually a solid mass of flame, which will in turn result in the temperature of the air discharged from the box 15 being raised to a considerable extent, and instead of mere 15 hot gases passing through the ports 12 flames will be in contact with the radiating surfaces of the various furnace sections, as a consequence of which the air, water or steam within these sections will have its temperature 20 raised to a high degree within a relatively short period of time. Furthermore, due to this result, the particles which are normally discharged from the flue, retained within the 25 same, or deposited on the various baffle surfaces of the boiler sections will be virtually entirely consumed, so that it does not become necessary to frequently clean the various portions of the furnace or the flues connected therewith, and, additionally, it will be feasible 30 to utilize low grades of fuel, which would otherwise be objectionable incident to the large discharge of smoke from the upper end of the flue.

When the furnace is once in operation, or, 35 in other words, when the flue and furnace parts have become well heated and there is consequently very little danger of a back draft through the flue 25, the valve 27 may be thrown to close the opening 28 and to uncover the opening 26, so as to draw a fresh, clean 40 air supply into the conduit, it being understood that with two openings it is usually only necessary to draw air in through the ashpit during the initial stages of combustion of the 45 fuel body within the firepot.

Due to the construction herewith suggested it is obvious that there will be very little, if any, danger of the unit which supplies the hot air becoming useless, due either to burning 50 out or to being damaged by coal or furnace utensils, etc., for the reason that it is well spaced from the upper level of the fuel body. As a consequence, it will not be subjected to intense temperature and it will not be in the 55 way of coal or utensils in their passage through the fire door. Further, in such position it will distribute the highly heated air in a more desirable manner than is usually the case in a complicated unit.

60 At this time it is also to be noted that due to the construction suggested it will be unnecessary, unless desired, to modify the furnace body or sections in any other respect than having one section interrupted throughout a

portion of its length, in order to provide an 65 opening for the firebox neck.

If it does become necessary to renew the airbox, this may be readily done by a person unskilled in the use of tools, and also without necessity of disassembling the furnace. More 70 particularly, it is only required that the box 15 be pulled towards the fire door, which can be accomplished by use of a poker or any other suitable implement. This movement may be continued until such time as the edge 75 of the rearwardly-extending portion 23 of the box clears the outer edge of the ledge 24, when it will be obvious that the outer end of the box will drop clear of the section 9. Upon continued movement the mouth 19 of the box neck will clear the upper edge of the 80 opening formed in the section 9, and thus it will be apparent that the whole box may readily be removed, it being only necessary to reverse the process, in order to supplant the 85 old box with a new one.

Finally, if desired, the opening 28 in the base may be dispensed with, and the air may at all times be drawn directly through the lower end of the conduit 25, it being furthermore obvious that, if desired, a damper 29 may be positioned within this conduit for controlling the flow of fluid therethrough. 90

From the foregoing it will be appreciated that the objects of the invention have been accomplished, and since certain changes may be made in the above construction, and different embodiments of the invention could be made, without departing from the scope thereof, it is intended that all matter contained in the above description, or shown in the accompanying drawings, shall be interpreted as illustrative and not in a limiting sense. 95

It is also to be understood that the following claims are intended to cover all of the generic and specific features of the invention herein described, and all statements of the scope of the invention which as a matter of language might be said to fall therebetween. 100

Having described my invention, what I claim as new and desire to secure by Letters Patent is:

1. In combination, a furnace having a combustion chamber defined by walls, an airbox within said combustion chamber, and means to support said airbox within said chamber, said means including a shoulder formed on one of said walls, a hook associated with another of said walls, and extending in a direction away from the first wall, a hook associated with said box and extending towards said shoulder, and an air intake member associated with said box and extending substantially in the same direction as the latter hook and engaging said shoulder. 115

2. In combination, a furnace comprising a casing and a section at the upper end of the 120

same providing a combustion chamber, one of said members being formed with a port, a portion of one of said members providing a substantially flat surface, an airbox, a hook forming a part of the same and engaging with said surface, and an extension forming a part of said box and filling said port, said parts having sliding engagement with each other whereby said box may be slid with respect to said furnace structure to effect a removal of said box from the chamber.

3. In a furnace, in combination, a casing, a horizontal section at the upper end of the same and providing a combustion chamber, an airbox within said combustion chamber, said section being provided with a supporting surface and a recessed portion adjacent the same, the rear of said furnace parts being formed with a port and a firedoor opening at the forward end thereof, an extension forming a part of said airbox and slidably projecting into said port, and a supporting member also forming a part of said box and slidably engaging the supporting surface of said section whereby when said box is moved towards said firedoor opening it will be detached from said furnace parts.

4. In combination, a furnace comprising a casing, a horizontal section at the upper end of the same and formed with an opening for the escape of products of combustion generated within the combustion chamber defined by said section and casing, one of the walls of the chambers being formed with a port adjacent said opening, an airbox, an extension forming a part of said airbox and

projecting across said opening and into said port into slidable engagement with the furnace parts, and quick-detachable means forming a part of said section and said airbox for suspending the latter from the former.

5. In combination, a boiler comprising a body and a section disposed above the same, said body and section providing a combustion chamber, said body being formed with a port and said section providing a recess in its under face and an air-supplying member positioned within said combustion chamber and including a hollow body having its lower face formed with openings for the escape of air, the end of said body extending into said port, and means extending from the upper face of said body and into the recess of said section for detachably supporting the same.

6. In combination, a boiler comprising a body and a section disposed above the same, said body and section providing a combustion chamber; said section being provided with a notch in its rear edge and with a recess in its under face forwardly of said notch; said body being formed with a port adjacent said notch, and an air-supplying member positioned within said combustion chamber and including a hollow body having its lower face formed with openings for the escape of air; the end of said body extending upwardly into said notch and rearwardly into said port; and means extending from the upper face of said body and into said recess of said section for detachably supporting the same.

In testimony whereof I affix my signature.
DWIGHT S. RICHARDSON.
